UNITED STATES PATENT OFFICE.

ISAAC D. WEAVER, OF LEBANON, PENNSYLVANIA, ASSIGNOR TO HIMSELF
AND BENJAMIN F. HARPEL, OF SAME PLACE.

ROTARY BLOWER.

SPECIFICATION forming part of Letters Patent No. 320,196, dated June 16, 1885.

Application filed March 4, 1884. (No model.)

To all whom it may concern:

Be it known that I, ISAAC D. WEAVER, of Lebanon, in the county of Lebanon and State of Pennsylvania, have invented a new and Improved Rotary Blower, of which the following is a full, clear, and exact description.

My invention consists of the construction and arrangement of parts as will be herein-after fully described and claimed.

Reference is to be had to the accompanying drawings, forming part of this specification, in which similar letters of reference indicate corresponding parts in all the figures.

Figure 1 is a transverse sectional elevation of my improved rotary blower. Fig. 2 is partly a side elevation and partly a longitudinal sectional elevation. Fig. 3 is an inside elevation of one of the covers of the cylinder. Fig. 4 is a front elevation of one of the wings, and Fig. 5 is an end elevation of a wing.

I make a cylindrical case, *a*, with an offset, *b*, or equivalent device in the inner periphery to let the air-pressure balance on both sides of the wings at the point where they begin to close, said case being also constructed with inlet-openings *c* and discharge-openings *d*; also, with an abutment, *e*, and a packing, *f*, between said openings to prevent the air from being forced back to the inlet-openings. In the center of this cylinder I arrange a drum, *g*, on a shaft, *h*, and close in said drum by heads *i* to the cylinder, in the center of which the shaft-bearings *j* are fitted by a flange, *k*, in an annular recess, *l*, surrounded by a flange, *m*, and secured by bolts *n* and adjusting-screws *o*, by which the bearings may be shifted from time to time to center the shaft. In the periphery of the drum I fit two or more wings, *p*, by a pivot, *q*, formed on the inner edge of the wings and working in a socket-groove in the hub suitably for the wings to close for passing the abutment and to open into the space for driving the air, and on each end of the wings I arrange an arm, *s*, with a roller, *t*, on the end of the arm running in a groove in the head *i*, suitably formed to open and close the wings as required in their rotation around the cylinder and past the abutment. The grooves are constructed with a section, *u*, on a large radius, along which the rollers pass to keep the wings closed while

passing the abutments, and with a section, *v*, on a smaller radius, in which the rollers pass to hold the wings open when forcing the air; also, with a section, *w*, along which said rollers run to open the wings, and also a section, *x*, in which said rollers pass to close the wings. Where the grooves extend radially beyond the drum, plates *y* are fitted in recesses *z* of the heads to cover the grooves and prevent the air from escaping back past the ends of the wing through the grooves and the recesses *a'* made in the heads for the arms *s*. The drum *g* is made with suitable recesses, *b'*, in which the wings close when passing the abutment, and the bottoms of the recesses and the sides of the wings closing into them are grooved, as shown in Fig. 1, to provide space in which oil or other fluid or solid matters that may happen to lodge between them may have space to prevent obstructing the closing of the wings. Inside of the drum I arrange an adjustable key, *c'*, on the face of a lug, *d'*, on the drum, and in suitable relation to each arm of the wings for a bearer to take the thrust of the wings from the rollers when forcing the air, and so that by careful adjustment of the wings the friction of the outer edges on the surface of the case may be limited as desired, and the wings may be adjusted as to the extent of their opening from time to time as the outer edges wear away. The keys *c'* are bolted to the sides of the lugs by bolts *e'*, fitted in slotted holes of the keys, and are connected to the ends of said lugs by adjusting-screws *d''* for enabling the keys to be accurately shifted. The arms, thus relieved of supporting the wings against the resistance of the air, have only to move the wings in closing and opening them, and therefore may be offset at *f'* beyond the ends of the drum into the recess *a'*, and may also be recessed at *g'* to run behind the covers *y*, and will still be sufficiently strong for the service required of them. The packing-plate *f* is fitted adjustably on the abutment *e* by means of slotted holes through it for the attaching-bolts *h'* to take up the slack from time to time.

To confine the pivots *q* of the wings *p* in their bearing-sockets in the drum, said pivots may have strap or loop hinges *p''*, fitted flush and loosely in sockets *p'*, around the pivots

and secured to the drum, and the pivots may be flanged at the ends or elsewhere, as shown at x' , to receive the keepers y' for securing the wing-pivots more firmly in place.

- 5 With these improvements in the construction of the rotary blowers considerable compression can be obtained to better advantage than can be effected with the common reciprocating compressors by avoiding the loss due to 10 the rise and fall of the valves, and the waste in the clearance spaces of the cylinder and passages.

The operation of the machine is as follows: The wings p swing out so as to close against 15 the inner periphery, a , of the drum immediately after passing the abutment e ; partly by the effect of centrifugal force, but mainly and positively by the rollers t of the wing-arms s passing along the inclined part of the cam- 20 groove from part u to part v , and force the air in advance of them out through discharge-openings d , the air being drawn in through 25 passages c by the suction behind said wings. When one wing has passed the abutment and 30 opened against the rim a , the one in advance has arrived at the point where it begins to close, and its roller t then runs along part x of the cam-groove with which said roller enters about the time the forward edge of the 35 wing reaches the depression b . The rear wing then takes the resistance of the air, the closing-wing being relieved by the opening which the depression makes to the back of the wing so that the closing of the wing for passing the

abutment is not opposed by the pressure of 35 the air. The wings thus open and close successively, the open one forcing the air while the closed one is passing the abutment, which is the means of permitting the escape of the compressed air back to the suction side of the 40 blower.

Having thus described my invention, I claim as new and desire to secure by Letters Patent—

1. The combination, in a rotary blower, of the cylinder a , having offset b and abutment e , heads i , having recesses a' and grooves $u v w x$, and drum g , having swinging wings p , hinged thereto, said wings having arms s , offset at f' , and rollers t , and said rollers t arranged to run in the grooves for opening and 50 closing the wings, substantially as described.

2. The combination of the adjusting-keys c' , attached to lugs d' of the interior of the drum, with the arms s of the wings p , pivoted in the periphery of the drum, substantially 55 as described.

3. The combination, with cylinder head i , provided with a flanged-recess, $l m$, of the shaft-bearing j , provided with the flange k , of less diameter than that of the said recess and 60 resting against the cylinder-head, screws o , passing through flange m into the cylinder-head, and screws n , passing through flange k into head i , substantially as set forth.

ISAAC D. WEAVER.
